KEY SET TABULATING MECHANISM

Application filed February 16, 1929. Serial No. 340,583.

This invention relates to tabulating mechanism for typewriters, and it has for its object to provide an attachment for the standard Underwood typewriter, by means of which tabular stops upon the rear of the typewriter may be set by the manipulation of an element disposed adjacent the keyboard of the typewriter, and in a position convenient of access by the operator. It is not broadly new, with me, to actuate the stops of a tabulating machine from the keyboard of the same. There is an Underwood typewriter known as the key set decimal tabulating machine, in which the tabulating stops are set from the keyboard of the machine. However, the widely used standard Underwood typewriter is so constructed that the tabulating stops must be separately manipulated and set by hand from the back of the machine, and the operator must turn the machine around, or else reach over the top of the same, to set these stops.

Under the present invention, I combine with existing portions of the standard Underwood typewriter, very simple and inexpensive elements, by virtue of which I am able to set tabulating stops upon said machines, from the front of the same.

In the accompanying drawings:

Fig. 1 is a view, partly in elevation and partly in section, of the elements constituting the present invention, looking from an end of the standard Underwood typewriter, and with certain portions of the latter illustrated in dotted lines,

Fig. 2 is a fragmentary plan view of the actuating member of the bichrome ribbon shift, hereinafter described,

Fig. 3 is a detail view of a spring engaged collar, hereinafter described,

Fig. 4 is a detail view of a fragment of the lift frame assembly shaft of the standard Underwood typewriter,

Fig. 5 is a rear view of the mechanism constituting the attachment of the present invention,

Fig. 6 is a plan view of an angle plate constituting the tabular stop, hereinafter described, and

Fig. 7 is a fragmentary view of a cranked shaft, hereinafter described,

Fig. 8 is a side elevation of the bichrome ribbon shift and associated parts, and

Fig. 9 is a view partly in elevation and partly in section of the tabulator rack, tabular stop plates, and associated parts.

In the standard Underwood typewriter, the bichrome ribbon shaft mechanism comprises an operating finger piece 5, such as is illustrated in Fig. 2, said finger piece being, in the known constructions, mounted upon an oscillating rod.

In carrying out the present invention, I substitute for said rod a tube or sleeve 6, the operating finger piece 5 being secured to said sleeve to oscillate the same to shift the ribbon mechanism in the same way as formerly. The tabular sleeve is then utilized as a mounting for a longitudinally slidable rod

7, having a head or button 8 upon its outer end, which is disposed at the front of the machine and in a position convenient of access by the operator. The inner end of the rod 7 is preferably provided with an enlarged head 9, which bears upon the crank extension 10, of a band 11. This band encircles the conventional lift frame assembly

shaft 12 of the typewriter, and carries a crank extension 13. A spring 14 connects the lower end of the crank extension 10 with a finger 15, of a collar 16, the latter being held by set screws 17, upon the sleeve 6. It is clear

that the spring 14 tends to thrust the rod 7 outwardly, the outward movement of such rod being limited by contact of the head 9 with the inner end of the sleeve 6.

It is also clear that if the operator presses the head or button inwardly, crank extension 10 will be moved against the tension of spring 14, and the crank extension 13 will move downwardly.

This downward movement of extension 13 is transmitted through a link 14^a to the crank arm 15^a, upon an oscillatory shaft 16^a. At a point further along in its length, this shaft 16^a is provided with a second crank extension 17^a. The shaft 16^a is an existing element of the present Underwood key set decimal tabulating machine, and I utilize this element in

the construction of the present device. The crank 17^a is pivotally connected at its outer end to a bar 18, the upper and lower ends of which are off-set from each other, as shown, 5 and which bar constitutes the key set decimal tabular stop setting slide of the present Underwood key set decimal tabulator. To the upper end of the bar I rigidly attach a stop set slide 19. This element 10 slides through slot 20^a of a tabular stop plate 20, which has a single stop tooth 21, upon its upper edge. This plate is carried by the conventional tabular frame fulcrum shaft or bar 22, of the standard Underwood typewriter which under my proposed arrangement is converted into a tabulator stop plate supporting shaft. That is to say, in the known type of machine, this bar rocks or oscillates upon its axis. Consequently, when 15 the tabulator key (not shown) of the standard Underwood typewriter is actuated, this bar 22 is rocked toward the left and swings the tooth 21 upwardly and inwardly into the path of movement of any of the set stops 23 of the decimal tabulator rack 24. This decimal tabulator rack is like a corresponding element of the Underwood key set decimal tabulating machine now on the market. That is to say, it comprises the rack bar, which carries 20 a large number of the stops 23, movable vertically through bar 24 from the full to the dotted line position. The slide 19 is provided with an end or finger 26, which overlies the line of stops 23, and when the slide 19 is drawn downwardly, by the operation of the key 8, the stop which happens to lie beneath the finger 26 will be thrust downwardly through bar 24, and into such position that when the tooth 21 is moved upwardly and inwardly, it will lie in the path of movement of 25 the depressed stops. The rack 24, and its associated stops are mounted upon the carriage of the standard Underwood typewriter, and take the place of the conventional tabulator rack of said standard typewriter.

When it is desired to set a given stop to cause the typewriter to begin its writing at a given point in the width of the sheet of paper being written upon, the operator moves 30 the carriage to bring such point upon the paper at the writing space, or point, of the typewriter, and then presses upon the key 8, thereby depressing the corresponding stop 23 of the rack bar. A brake consisting of a 35 plate 27 and a leather brake shoe 28, is yieldably secured to the outer face of the tabulator stop plate 20, by means of a pair of screws 29. Springs 30 bear between the heads of these screws and the outer face of plate 27, and 40 tend to move the plate 27 toward tubular stop plate 20. Consequently, when the bar 22 is oscillated to move tooth 21 upwardly and inwardly, the leather brake shoe 28 is moved against the smooth outer face of the 45 rack bar 24, and frictionally engages the

same during the movement of the carriage. This prevents undue acceleration of the carriage and prevents excessive shock and jar when the depressed stops strike against tooth 21.

Further, it is to be noted that the action of the brake is controllable by the operator, since the greater the pressure applied to the tabular key of the typewriter in rocking element 22, the greater the pressure exerted by 75 the brake shoe. The position of the brake may further be adjusted by varying the tension of the springs 30, under manipulation of the screws 29.

In the drawings, I have illustrated the 80 existing portions of the standard Underwood typewriter in dotted lines, and have illustrated the elements of the present attachment in full lines. The members 15, 16, 17 and 18 have been illustrated in full lines because 85 they are taken from the key set decimal tabulating machine, and are not ordinarily present in the ordinary standard Underwood machine, to which this attachment relates.

The same is true with relation to the rack 90 24 and stops 23. While they are of a known construction, they are found in the key set decimal tabulating machine, and not in the usual standard typewriter.

From the foregoing description it will be 95 apparent that I have utilized many of the existing parts of the standard Underwood typewriter, and have combined therewith very simple and inexpensive attachments, by virtue of which the owners of the relatively 100 simple standard machine may have all of the advantages of the key set tabulator.

It is to be understood that the invention is not limited to the particular arrangement herein shown and described, because other 105 ways will readily suggest themselves to persons skilled in the art of providing an actuating means extending to the front of the typewriter for actuating the slide 19. Consequently, it is to be understood that the invention includes within its purview whatever changes fairly come within either the terms or the spirit of the appended claims.

What I claim and desire to secure by Letters Patent is:

1. The combination with a typewriter, of a stop bar movable with the carriage thereof and comprising a plurality of depressible stops, a member adapted to engage said stops when said member is moved downwardly, a ribbon shift element of tubular formation extending from the front toward the rear of the typewriter, a rod longitudinally movable through said ribbon shift element and exposed for operation at its outer end, and connections operated by the inward thrust of said rod for moving said stop setting member downwardly.

2. The combination with a typewriter having a lift frame assembly shaft, of a stop bar 130

movable with the carriage thereof and carrying a plurality of tabulator stops, a member, the movement of which sets said stops, and means for actuating said member from the front of the typewriter, comprising a shaft having a pair of cranks, said member being connected to one of said cranks, a link connected to the other of said cranks, a part mounted for oscillation upon the lift frame assembly shaft of the typewriter, a crank extension carried by said part to which said link is pivoted, a second crank extension extending from said part, spring means tending to move the last named crank extension outwardly, and means accessible from the front of the typewriter for thrusting inwardly upon the last named extension and against the tension of said spring.

3. The combination with a typewriter having a lift frame assembly shaft, of a stop bar movable with the carriage thereof and carrying a plurality of tabulator stops, a member, the movement of which sets said stops, and means for actuating said member from the front of the typewriter, comprising a shaft having a pair of cranks, said member being connected to one of said cranks, a link connected to the other of said cranks, a part mounted for oscillation upon the lift frame assembly shaft of the typewriter, a crank extension carried by said part to which said link is pivoted, a second crank extension extending from said part, spring means tending to move the last named crank extension outwardly, means accessible from the front of the typewriter for thrusting inwardly upon the last named extension and against the tension of said spring, said last named means comprising a tubular ribbon shift element, and a rod movable through said ribbon shift element.

4. The combination with a typewriter having a lift frame assembly shaft, of a stop bar movable with the carriage thereof and carrying a plurality of tabulator stops, a member, the movement of which sets said stops, and means for actuating said member from the front of the typewriter, comprising a shaft having a pair of cranks, said member being connected to one of said cranks, a link connected to the other of said cranks, a band mounted for oscillation upon the lift frame assembly shaft of the typewriter, a crank extension carried by said band to which said link is pivoted, a second crank extension extending from said band, spring means tending to move the last named crank extension outwardly, means accessible from the front of the typewriter for thrusting inwardly upon the last named extension and against the tension of said spring, said last named means comprising a tubular ribbon shift element, and a rod movable through said ribbon shift element, the outward movement of said

rod under the influence of said spring being limited by the tubular ribbon shift element.

5. The combination with a typewriter, of a stop bar movable with the carriage thereof and comprising a plurality of stops adapted to be projected beyond said bar, a member adapted to engage said stops and move them when said member is moved, a ribbon shift element extending from the front toward the rear of the typewriter, an operating member associated with and supported by said ribbon shift element and operable from the front of the typewriter, and connections between the said operating member and the first named member for actuating said first named member to move said stops.

6. The combination with a typewriter, comprising a lift frame assembly shaft, of a stop bar movable with the carriage thereof and comprising a plurality of stops adapted to be projected beyond said bar, a member adapted to engage said stops and move them when said member is moved, a ribbon shift element extending from the front toward the rear of the typewriter, an operating member associated with and supported by said ribbon shift element and operable from the front of the typewriter, and connections between the said operating member and the first named member for actuating said first named member to move said stops, said connections comprising an oscillatory shaft having a pair of crank arms thereon, one of said crank arms being connected to the first named member, a part mounted for oscillation upon the lift frame assembly shaft of the typewriter, a crank extension carried by said part, a link connecting the crank extension with the other crank of the oscillatory shaft, and a second crank extension from said part that is engaged and moved by the operating member.

7. The combination with a tabulator stop plate supporting shaft of a tabulator stop plate, substantially L-shaped, one leg of which is secured to the tabulator stop plate supporting shaft, a rack bar carrying a plurality of depressible stops overlying the free edge of the tabulator stop plate, a brake secured to the tabulator stop plate and movable with said stop plate to bring it into engagement with the outer face of the rack bar, and a stop setting element which passes through the tabulator stop plate and is provided with an end overhanging the said rack bar.

8. A tabulator stop plate of substantially L-shape, comprising a substantially vertical leg, said horizontal leg being transversely slotted, said vertical leg being provided with a stop tooth along its upper edge.

9. A structure as recited in claim 8, in combination with a brake carrying member secured to the outer face of the tabulator stop

plate and carrying at its free end a brake shoe.

10. A structure as recited in claim 8, in combination with a brake carrying plate, yieldably secured to the outer face of the tabulator stop plate.

11. The combination with a typewriter and its carriage of a rack bar carried thereby, provided with a plurality of depressible stops, an oscillatory tabulator stop plate supporting shaft, the tabulator stop plate comprising a lateral and a substantially vertically extending portion, the former being secured to said shaft and being rocked by the movement of said shaft to carry its upper edge toward the said rack bar, a brake yieldably secured to the outer face of the stop plate, comprising a brake shoe adapted to be moved into contact with the outer face of the rack bar when the tabulator stop plate is rocked upwardly, a stop plate setting element comprising a bar extending through the tabulator stop plate and carrying an overhanging end adapted to engage and depress the stops of the rack bar, and means for imparting downward movement to said bar from a point adjacent the key board of the typewriter.

30 In testimony whereof I affix my signature.
